2 Sheets-Sheet 2

UNITED STATES PATENT OFFICE.

EMERY H. FAHRNEY, OF CHICAGO, ILLINOIS.

SIGNBOARD.

Application filed April 14, 1923. Serial No. 631,974.

To all whom it may concern:

Be it known that I, EMERY H. FAHRNEY, a citizen of the United States, residing at Chicago, in the county of Cook and State 5 of Illinois, have invented certain new and useful Improvements in Signboards, of which the following is a specification.

Heretofore sign boards, and especially large sign boards have been constructed of 10 a frame to which are secured panels usually of sheet material, carrying thereon the matter to be displayed. These panels being subjected at all times to the elements often buckle or warp, with the result that the sign 15 board not only becomes unsightly but the advertising matter displayed thereon becomes distorted. It then becomes necessary to remove the buckled panel and substitute a new one therefor, which latter will in a comparatively short time also buckle or become warped.

It is one of the objects of the present invention to provide an improved sign board of this character embodying panels constructed of sheet material, and improved 25 means for securing the panels in position upon the frame, whereby the panels will be supported by or anchored at one end to the supporting structure, while the other end of 30 the panel is detached from or free with respect to the supporting structure.

A further object is to provide an improved sign board of this character embodying means operating to exert a stress upon the 35 free end of the panel in such a manner as to normally tend to maintain the body of the panel rigid or taut and thereby overcome any tendency of the elements to buckle or warp the panel.

40 A further object is to provide an improved sign board of this character in which the panels may be separately and readily removed when desired and as readily replaced in position.

45 To the attainment of these ends and the accomplishment of other new and useful objects as will appear, the invention consists in the features of novelty in substantially the construction, combination and arrangement 50 of the several parts hereinafter more fully described and claimed and shown in the accompanying drawings illustrating this invention, and in which—

55 Figure 1 is a perspective view of a portion of a sign board constructed in accordance with the principles of this invention, por-

tions of the board and one of the panels being removed.

Figure 2 is a vertical sectional view taken 60 on line 2—2, Figure 1.

Figure 3 is a rear elevation of a portion 65 of the supporting structure and one of the panels.

Figure 4 is a perspective view taken from 70 the front of one of the panels.

Figure 5 is a view similar to Figure 1, showing the first step of inserting or placing 75 one of the panels in position upon the supporting structure.

Figure 6 is a view showing one of the 70 panels replaced in position.

Figure 7 is an enlarged, vertical sectional 75 view on line 7—7, Figure 5.

Figure 8 is a detail, horizontal, sectional 80 view taken on line 8—8, Figure 5.

Figure 9 is a horizontal, sectional view 85 taken on line 9—9, Figure 7.

Referring more particularly to the drawings the numeral 15 designates a supporting structure for the sign which may be of any 80 desired size and configuration and constructed of any suitable material. Arranged at the top of the structure is a moulding 16, which is spaced from the supporting structure so as to form a recess 17 between the 85 moulding and the supporting structure and into which recess one end of the panels are inserted in a manner to be hereinafter set forth. Spaced below the moulding 16 for any desired distance is a supporting ledge 18, upon which the panels are supported.

The frame thus formed may be of any desired size and the panels 19 are adapted to be arranged within the frame. These panels 90 may be of any desired size and configuration but are preferably of a size as to enable them to be readily handled. As the construction of each of the panels is the same, the description of one will apply 95 equally as well to them all.

The panel 19 embodies a body portion 100 which is constructed of sheet material preferably of a slightly flexible nature, such as metal or the like, although any other sheet material suitable for the purpose may be employed.

Secured adjacent one end of the panel is a re-inforcing member 20 preferably in the 110 form of a channel iron. This channel iron is arranged at the rear of the panel and the panel is secured thereto in any desired or suitable manner preferably by means of fas-

tening devices 21. Arranged at the opposite end of the panel is another channel iron 22, which extends across the back thereof and is secured to the end of the panel by means of 5 suitable fastening devices 23. Anchored to the channel iron 20 is a bar or member preferably constructed of sections 24—25, the proximate ends of these sections being preferably adjustably connected in any suitable 10 manner, such as by means of a turn buckle 26. The free end of the member 24 is anchored to the channel bar in any suitable manner preferably by passing through one of the flanges thereof and is held in position 15 by means of suitable fastening nuts or collars 27, arranged on opposite sides of the flange of the channel iron.

Connected with the free end of the member 25 is a yoke or clip 28. This yoke or 20 clip is preferably pivotally connected as at 29 to permit of a slightly yielding movement of the clip or the yoke with respect to the member 25.

An elastic element 30, preferably in the 25 form of a leaf spring is connected intermediate its ends with the yoke or clip 28, the free extremities 31 of the element 30 abutting one edge or flange of the channel member 22 at the opposite end of the panel 30. As a means for maintaining the element 30 against displacement with respect to the channel member 22, any suitable yielding fastening means may be provided, such as 35 a key hole slot 32, provided in each end of the element 30. Carried by the channel member 22 are headed bolts 33, which depend therefrom and are adapted to enter the key hole slots 32.

The elastic element 30 is normally placed 40 under tension by reason of the fact that one end of the member 24 is anchored to the channel 20 and the elastic element being connected with the other member 25 and resting against the channel 22 will exert its 45 stress upon the channel member 22 in a direction lengthwise of the panel 19, and thereby hold the panel rigid or taut. The stress of the elastic member 30 may be varied by adjusting the turn buckle 26. By 50 the provision of the key hole slots 32, the elastic element 30 may be readily detached from the channel member 22, whenever desired.

If desired and as an additional means for 55 preventing buckling, warping, or twisting of the body portion of the panel 19, one or more bars or members 34 may be provided, and to that end the flanges of the channel member 20 may be provided with registering 60 openings, through which one end of the member 34 passes. Fastening pins 35 may be passed through suitable openings in the member 34, within the channel member 20 and in proximity to the flanges thereof for 65 maintaining the member 34 against longi-

tudinal movement with respect to the channel member 20. The channel member 22 is also provided with registering openings through which the free end of the member 34 loosely passes. Any number of these 70 members 34 may be provided but it is preferable to provide one such member adjacent each of the longitudinal edges of the panel.

This construction will not interfere with 75 the movement of the free end of the panel 19 with respect to the members 34.

In use, the matter to be displayed may be placed upon the panel when the same is detached from the supporting structure and 80 all of the panels may be prepared and then placed upon the supporting structure.

In assembling, each of the panels is placed upon the supporting structure by first passing the upper end thereof beneath the moulding 16 and into the space 17, as shown in Figure 5, after which the lower edge of the panel is placed upon the supporting ledge 18 and then moved backwardly to a position to preferably abut a stop 36 arranged at the 90 rear of the ledge 18 or into the position shown in Figure 6. Any suitable means may be provided for holding the lower edge of the panel from moving forwardly upon the ledge 18. A suitable and efficient means for that purpose embodies a plug or dowel pin 37, which is adapted to be inserted in an opening 38 through the ledge 18 and arranged in advance of the face of the lower 95 end of the panel, as shown more clearly in 100 Figure 6.

If desired the lower edges of the panel may be covered or protected by means of a suitable moulding 39, which may be of a continuous strip as shown in Figure 1, or may be constructed in sections 40 as shown in Figure 5. If constructed in the continuous strip the moulding will extend across the base of all of the panels but if constructed in sections 40, as shown in Figure 110 5, there may be provided a section of moulding for each panel. The moulding is connected with the supporting ledge for pivotal movement with respect thereto in any desired or suitable manner such as by 115 means of hinges 41 to permit the moulding to be freely moved into and out of position.

The lower face 42 of the moulding is so constructed that when the moulding is folded against the end of the panel and into the 120 position shown in Figure 7, it will extend over the dowel pin 37 and a space 43 will be formed between the lower edge of the panel and the moulding for the reception of the end of the dowel pin.

When it is desired to remove the panel, the moulding, or the respective sections thereof, may be swung about their hinges to the position shown in Figure 5, after which the 125 dowel 37 may be removed to permit the 130

lower edge of the panel to be moved outwardly as shown in Figure 5, after which the panel may be readily detached.

With this improved construction it will be

- 5 manifest that the tension or stress of the elastic member 30 will at all times be exerted upon one end of the panel 19 and inasmuch as the stress of this elastic member is also exerted upon the other end of the panel,
- 10 through the medium of the anchoring of the member 24 to the channel 20, it will be readily seen that the body portion of the panel will be held rigid or taut, and will thereby hold the panel against warping or twisting
- 15 under the influence of the elements. This construction also permits of the use of comparatively light sheet material for use in constructing the panels. This construction also permits the painter or illustra-
- 20 tor to produce the design or matter to be displayed upon the sign before the panels are assembled upon the supporting structure and when any one or more of the panels become injured or the matter displayed there-
- 25 on becomes disfigured any one or more of the panels may be readily removed without interfering with any of the other panels.

If desired the proximate longitudinal edges of adjacent panels may be interlocked, that is to say, one of the panels may be provided with a lip or projection 44 (see particularly Figure 8) which is adapted to project behind the edge of the next adjacent panel and at the same time these lips will not interfere with the removal of the panels. These lips are not necessary for a successful operation of this device but may be employed if desired.

While the preferred forms of the invention have been herein shown and described, it is to be understood that various changes may be made in the details of construction and in the combination and arrangement of the several parts, within the scope of the claims, without departing from the spirit of this invention.

What is claimed as new is:

1. A sign board embodying a supporting structure, a panel constructed of sheet material and supported by one edge upon the said structure, the opposite edge of the panel being free with respect to the supporting structure, resilient means operating upon the said free edge of the panel for maintaining the body portion of the panel taut, and means whereby the stress of the said resilient means may be varied.

2. A sign board embodying a supporting structure, a panel constructed of sheet material and supported by one edge upon the said structure, the opposite edge of the panel being free with respect to the supporting structure, resilient means operating upon the said free edge of the panel for maintaining the body portion of the panel taut,

means detachably securing the said resilient means to the said free edge of the panel, and means whereby the stress of the resilient means may be varied.

3. A sign board embodying a supporting structure, a panel constructed of sheet material and supported by one edge upon the structure, the opposite edge of the panel being freely movable with respect to the supporting structure, a tensioning device for maintaining the body of the said panel taut, the said tensioning device being connected with the said adjustable end of the panel and also with a fixed abutment, and means whereby the stress of the said tensioning device may be varied.

4. A sign board embodying a supporting structure, a panel constructed of sheet material and supported by one edge upon the structure, the opposite edge of the panel being freely movable with respect to the supporting structure, a tensioning device for maintaining the body of the said panel taut, the said tensioning device being connected with the said adjustable end of the panel and also with a fixed abutment, and means forming a guide for the said adjustable end of the panel.

5. A sign board embodying a supporting structure, a panel constructed of sheet material and supported by one edge upon the structure, the opposite edge of the panel being freely movable with respect to the supporting structure, a tensioning device for maintaining the body of the said panel taut, the said tensioning device being connected with the said adjustable end of the panel and also with a fixed abutment, and embodying a resilient element and a rigid element, the latter operating to place a stress upon the said resilient element.

6. A sign board embodying a supporting structure, a panel constructed of sheet material and supported by one edge upon the structure, the opposite edge of the panel being freely movable with respect to the supporting structure, a tensioning device for maintaining the body of the said panel taut, the said tensioning device being connected with the said adjustable end of the panel and also with a fixed abutment, and embodying a resilient element and an adjustable element, the latter operating to place a stress upon the said resilient element and being adapted to vary the said stress.

7. A sign board embodying a supporting structure, a panel constructed of sheet material, means supporting one edge of the panel upon the said structure, the other end of the panel being freely movable with respect to the supporting structure, a tensioning device embodying a resilient element, and means anchoring the said element to a fixed abutment whereby the stress of the resilient element will be exerted upon

the said freely movable edge of the panel, the said tensioning device being substantially disposed within the confines of the edges of the said panel.

- 5 8. A sign board embodying a supporting structure, a panel constructed of sheet material, means supporting one edge of the panel upon the said structure, the other end of the panel being freely movable with respect to the supporting structure, a tensioning device embodying a resilient element, means anchoring the said element to a fixed abutment whereby the stress of the resilient element will be exerted upon the 10 said freely movable edge of the panel, the said tensioning device being substantially disposed within the confines of the edges of the said panel, and means whereby the stress of the said tensioning device may be varied.
- 15 9. A sign board embodying a supporting structure, a panel constructed of sheet material, means supporting the panel by one edge upon the said structure, the opposite edge of the panel being freely movable with respect to the supporting structure, a shoulder adjacent the last recited edge of the panel, an anchor member, a fixed abutment adjacent the supporting edge of the panel and to which abutment the said anchor member is connected, and a resilient element connected with the anchor member and engaging the said shoulder on the panel for maintaining the panel substantially rigid or taut.

- 20 10. A sign board embodying a supporting structure, a panel constructed of sheet material, means supporting the panel by one edge upon the said structure, the opposite edge of the panel being freely movable with respect to the supporting structure, a shoulder adjacent the last recited edge of the panel, an anchor member, a fixed abutment adjacent the supporting edge of the panel and to which abutment the said anchor member is connected, a resilient element connected with the anchor member and engaging the said shoulder on the panel for maintaining the panel taut, and means for varying the stress of the said resilient element.

- 25 11. A sign board embodying a supporting structure, a panel constructed of sheet material, means supporting the panel by one edge upon the said structure, the opposite edge of the panel being freely movable with respect to the supporting structure, a shoulder adjacent the last recited edge of the panel, an anchor member, a fixed abutment adjacent the supporting edge of the panel and to which abutment the said anchor

member is connected, and a resilient element 60 connected with the anchor member and engaging the said shoulder on the panel for maintaining the panel taut, the said anchor member embodying sections adjustable one with relation to the other to vary the stress 65 of the said resilient element.

12. A sign board embodying a supporting structure, a panel constructed of sheet material, said panel being supported by one end upon the said structure, the opposite 70 end of the panel being free with respect to the supporting structure, means cooperating with the said free end of the panel for exerting a stress in a direction lengthwise of the panel, and one or more guide rods extending 75 across the back of the panel for assisting in maintaining the panel against buckling.

13. A sign board embodying a supporting structure, a panel constructed of sheet material, said panel being supported by one end 80 upon the said structure, the opposite end of the panel being free with respect to the supporting structure, means co-operating with the said free end of the panel for exerting a stress in a direction lengthwise of the panel, and one or more guide rods extending 85 across the back of the panel for assisting in maintaining the panel against buckling, one end of the rods being connected with one end of the panel, the other end of the rods having a loose connection with the panel whereby one end of the said panel and the adjacent portions of the rods will be 90 movable one with relation to the other.

14. A sign board embodying a supporting 95 structure, a supporting ledge on the structure, an overhanging projection spaced above the said ledge, a panel member, one edge of the panel being adapted to be inserted under the said overhanging projection, to permit the opposite edge of the panel 100 to be moved backwardly upon the said ledge, there being an opening through the ledge in advance of the lower edge of the panel when the latter is positioned upon the ledge, a removable fastening device adapted to be inserted in said opening in advance of the adjacent edge of the panel, and a moulding 105 hinged to the said ledge to be moved out of the way to permit the lower edge of the panel to be moved forwardly, said moulding being adapted to be folded over the said fastening device and against the lower end of said panel.

In testimony whereof, I have hereunto 115 signed my name to this specification, on this 12th day of April, 1923.

EMERY H. FAHRNEY.
